UNITED STATES PATENT OFFICE

STUART PARMELEE MILLER, OF ENGLEWOOD, NEW JERSEY, ASSIGNOR TO THE BARRETT COMPANY, OF NEW YORK, N. Y., A CORPORATION OF NEW JERSEY

DISTILLATION OF TAR

Application filed February 15, 1928. Serial No. 254,356.

This invention relates to improvements in the distillation of tar and the production of pitches and oils therefrom and from coal distillation gases, and includes a new method of tar distillation and of pitch and oil production and improved apparatus therefor. More particularly the invention relates to the recovery of pitch and oil products at coal-carbonization and distillation plants such as 10 by-product coke ovens and gas retort plants.

In the ordinary operation of by-product coke ovens the gases produced by the coking operation pass from the individual ovens through uptake pipes and goose-necks to a 15 collector main common to the ovens of the battery. The coke-oven gases which leave the ovens at temperatures from 600° to 700° C. or higher are cooled in the collector main and in condensers connected therewith to separate 20 tar constituents therefrom. The separated coal tar is commonly shipped to tar-distillation plants where it is subjected to distillation to produce pitches and various other products.

Owing to the high temperature of the gases from the coke ovens, and particularly because of the large amount of heat carried thereby, the successful operation of the collector main in connection with these ovens has always 25 been a serious problem. The heat carried by the gases is sufficient to distill many times as much tar as is produced from the gases. A certain amount of heavy tar or pitch tends to separate in the collector main and, unless 30 precautions are taken to prevent it, such tar or pitch is subjected to the distilling effect of the gases at high temperature with the resulting formation in the main of hard pitch which can in some cases be removed only by 35 shutting down the plant and scraping or digging it out. It is customary to flush the main with a mixture of tar and ammonia liquor or with ammonia liquor alone, but this practice does not always avoid the difficulty. In fact, 40 the use of water or ammonia liquor may aggravate the trouble in some cases because the pitches formed in the main are insoluble in water or ammonia liquor and hence are not flushed out unless a large amount of liquor or 45 of tar and liquor is employed.

The use of a large quantity of ammonia liquor in the collector main results in rapidly lowering the temperature of the gases. Thus, by spraying ammonia liquor into the collector main in sufficient quantity to prevent accumulations of pitch therein, the temperature of the gases may be so reduced that a considerable proportion of the valuable oil constituents which are present in the gases is condensed and thrown down with the tar and 50 may be recovered therefrom only by subsequent distillation.

The present invention provides an improved method and apparatus in which pitch and oil can be recovered directly and continuously from the coal distillation gases, and in which tar is also distilled continuously by the gases to produce pitch at the coal-carbonization plant, such as a by-product coke-oven or gas retort plant. The 55 invention includes improvements in the operation of the collector main of a coal distillation plant whereby advantage can be taken of the heat carried by the coal distillation gases to distill tar and oil and to separate volatile products therefrom so that the latter can be recovered independently of the pitch which then constitutes a separate product of the operation; and it includes also improvements in the treatment of the coal distillation gases for the direct recovery of merchantable pitch and oil products therefrom.

The present invention includes the separation from the hot gases of substantially all solid and tarry constituents, leaving only 60 relatively clean oil vapors therein which upon condensation, yield clean oils adapted to be utilized in the trade without further distillation or other treatment.

According to the present invention the hot 65 coke-oven gases as they come from the coke ovens are utilized for the distillation of tar and the separation of vaporizable oils therefrom by passing the gases through the collector main and by maintaining therein and 70 circulating therethrough continuously a large and constantly changing body of tar to be distilled; and the still hot gases are then subjected to a scrubbing treatment while still at a high temperature to remove suspended 75

pitch particles therefrom and to leave oil vapors therein, which are subsequently recovered by condensation.

The tar supply for the collector main operation can be introduced into the main and circulated therethrough in sufficient volume to prevent too great distillation thereof and the consequent formation of solid hard pitch in the main. In circulating through the main the temperature of the tar is raised owing to its contact with hot coal distillation gases flowing therethrough, and distillation of the tar is effected to a greater or less extent so that the more volatile constituents are separated therefrom and are carried away with the hot gases. The pitch resulting from the distillation may be withdrawn from the main and recirculated therethrough for further distillation. The extent of the distillation effected may be regulated and consequently the character of the pitch produced can be modified as desired to produce salable pitch products.

The river of tar and pitch flowing continuously through the collector main will be heated by the hot gases and its temperature may be raised considerably. Part of the heat is employed, however, in vaporizing oil constituents of the tar without corresponding increase in the temperature thereof so that the maximum temperature of the tar and of the resulting pitch may be considerably below that of the gases. To avoid accumulation of hard pitch in the main it is important that a large volume of tar or pitch be circulated actively and continuously through the main, particularly when the tar or pitch in the main is not effectively agitated. The heat available in the gases is such as to insure the heating of the tar or pitch to a temperature at which it is thinly fluid so that it can be circulated easily. Moreover, the hot tar or pitch readily dissolves any deposits of solid hard pitch in the main and accumulation thereof is thus avoided.

Indiscriminate cooling of the gases in the collector main is to be avoided, but it may be desirable to introduce a limited amount of water or ammonia liquor, for example, against the valves in the uptake pipes for the purpose of cooling the gases to a predetermined and regulated extent. The regulation of the cooling effect can be accomplished more readily with water or ammonia liquor because of the higher specific and latent heats of water as compared to those of tar and oils. Cooling of the gases to a regulated extent can also be accomplished by the introduction of oil with the tar. Thus, a proportion of the oil recovered from the gases can be returned to the collector main and mingled with the tar or pitch therein. The distillation of this oil in a collector main will absorb heat from the gases and thus permit the maintenance of the desired temperature therein.

The distilling capacity of the gases from a single coke oven battery is greatly in excess of that required for the distillation of the amount of tar which a single coke oven battery produces, even where the only contact between the gases and tar or pitch is surface contact of the circulating stream of tar or pitch, without atomizing or spraying the tar or pitch into the gases. Consequently, to maintain the operation as hereinbefore described, it is ordinarily necessary to provide an amount of tar very much in excess of that produced by the single battery which is so operated. The tar employed may be that produced by another coke oven battery or it may be tar derived from other sources such as gas retorts, vertical retorts and water-gas sets. Such tar may be mingled with tar from the battery or it may be introduced independently and circulated through the main for the purpose of producing pitches having different characteristics from those derived from coke oven tar. If tars from different sources are mingled and introduced to the collector main for distillation in the manner described, composite pitches will be produced and in this manner products having a greater or smaller proportion of free carbon than normal coke oven pitches can be prepared. Composite oils will also be obtained from subsequent treatment of the gases.

The hot gases flowing through the collector main will be cooled partially by transfer of heat to the tar or pitch undergoing distillation, and the gases will be enriched in oil constituents derived from the distillation of the tar or pitch. The gases will, however, leave the collector main still at relatively high temperature, e. g., at a temperature around 300° C. or 350° C. or higher, and will carry in addition to the oil vapors a certain proportion of pitch particles in the form of "fog", together with solid particles of coal, coke, etc., which are carried over from the coke ovens.

In the practice of the invention, it is not intended that the gases flowing through the collector main will be radically cooled to a low temperature, or that the maximum distilling effect of the gases upon the tar or pitch circulating through the collector main will be employed. The collector main operation is intended rather to insure that the gases passing therethrough are maintained at a high temperature and that the collector main itself is kept free from accumulations of hard pitch. More or less distillation of the circulating river of tar or pitch will, however, be obtained, and the circulating tar or pitch will be sufficiently hot and thinly fluid to promote effective distillation by surface contact with the hot gases, with resulting enrichment of the gases in oil vapors. The hot gases leaving the collector main will there-

fore still contain suspended pitch particles and oil vapors, including a large part of the oil content of the original gases in vapor form, together with the vapors resulting from the distillation of the tar and pitch in the collector main.

According to the present invention, the hot gases escaping from the collector main, and still contaminated with suspended pitch particles, and containing a large part of the oils in vapor form, are subjected to a scrubbing treatment at a high temperature, e. g., with hot tar or pitch, to separate suspended pitch and solid particles therefrom while still leaving a large part of the oils in vapor form. Such treatment at a high temperature recovers the pitch content of the gases in the form of merchantable pitch of regulated melting point, and leaves cleaned gases free or relatively free from heavy tar and pitch constituents, but containing a large proportion of oil vapors which can be subsequently recovered therefrom by cooling and condensation.

The scrubbing of the gases at a high temperature can be effected with hot tar or pitch, and further distillation of the tar or pitch may take place during such scrubbing. If cold tar is employed in the scrubber, it may cool the gases too much and result in condensation of too great a proportion of the oil content carried by the hot gases. It is accordingly desirable, if tar is employed, to preheat the tar to a sufficiently high temperature to avoid or prevent or minimize such condensation. Instead of using tar, hot pitch can be employed, and the pitch can be recirculated through the scrubber, with temperature adjustment, by heating or cooling, to maintain it at a substantially constant high temperature. The pitch produced in the collector main may be employed in the scrubber for scrubbing and cleaning the gases, particularly as a large excess of hot pitch is kept in circulation through the collector main. The pitch circulated may be of similar temperature and composition to that scrubbed from the gases, but it is not essential that it should be, and more or less distillation of the pitch or tar may take place in the scrubber simultaneously with the scrubbing and cleaning of the gases and the removal of suspended pitch particles therefrom.

The melting point of the pitch produced from the gases in the scrubber can be regulated by regulating the amount and temperature of the scrubbing pitch employed, and also by regulating the temperature of the gases passing through the collector main and into the scrubber. When the gases are not scrubbed with tar or pitch in the collector main, but have only surface contact with the river of hot tar or pitch circulating therethrough, they pass through the collector main and enter the scrubber at a high temperature, sufficiently high to enable them to distill tar

or pitch and remove a considerable amount of oils therefrom, without cooling the gases below the temperature at which they will retain a large proportion of oils in vapor form. The scrubber in such case is an effective still for distilling tar to produce pitch, or for distilling pitch to produce pitch of higher melting point, simultaneously with the recovery of pitch from the gases.

The invention can be applied to ordinary coke oven plants such as Semet-Solvay, Koppers plants, etc., as well as to gas retort plants, without any considerable modification thereof, the usual standard equipment being employed with the addition of a scrubber or scrubbers for the purpose of cleaning the gases and of means for circulating tar and pitch through the collector main. Thus, the ovens of the battery may be connected in the usual manner by uptake pipes and goose-necks to the collector main and the gases may be conveyed therefrom through the scrubber or scrubbers and thence through a cross-over main to the ordinary condensing system. Insulation of the uptake pipes, collector main and scrubbers, etc. may be necessary or desirable to insure treatment and utilization of the gases while still at a high temperature. Suitable storage tanks for the tar or pitch to be circulated through the collector main and a pump or pumps with connections to the collector main will be provided to permit the maintenance of the required volume of tar or pitch in the main during the operation thereof.

The scrubber is disposed preferably closely adjacent to the collector main in order that the temperature of the gases may not be reduced unduly before removal of the pitch constituents is accomplished. The scrubber may be insulated to prevent loss of heat from the gases.

The scrubber may consist of a suitable tower through which the gases ascend in contact with a descending stream of tar, pitch or oil flowing over suitable baffling devices to insure intimate contact between the tar or pitch and the gases in the scrubber. The tar or pitch may be withdrawn from the scrubber and returned for further use therein.

The scrubber may in some cases be operated at a temperature equal to or somewhat higher than the gas temperature and the tar, pitch or oil supplied thereto will in such cases be at such a temperature as to avoid reduction of the quantity of the oil vapors in the gases or to add to the quantity of oil vapors, due to distillation of the scrubbing medium. The tar, oil or pitch may be heated by a heat exchanger supplied with heat through any suitable medium.

The scrubber may be used also as a means for altering the composition of the scrubbing medium as well as for condensing vapors and for removing suspended pitch

particles from the gas stream. If, for example, it is desired to convert an oil or tarry oil of relatively wide boiling range into an oil of relatively narrow range, and combine it at the same time with heavy tar or pitch from the gases, the oil will be circulated through the scrubber at such a temperature as will cause the light oil in the scrubbing oil to be absorbed by the gases. Likewise, the gases may give up to the scrubbing oil some of the heavier condensable vapor as well as suspended heavy pitch or tar particles. The scrubbing oil will thus be freed of light oils to the desired extent and will be enriched in heavy oils and heavy tar or pitch constituents. The gases will be enriched in light oil vapors and will be freed from pitch and to some extent from heavy oil vapors. Sensible heat of the coke-oven gases and sensible and latent heat of the condensable vapors are removed as latent heat of vaporization by volatilization of the lower boiling constituents of the scrubbing medium. The process in this case depends upon an interchange of heat between higher boiling condensing oils and lower boiling vaporizing oils, the higher boiling oils being recovered together with admixed pitch as a liquid product at the bottom of the scrubber and the lower boiling oils being withdrawn as vapors with the gases.

The scrubber in such a case functions somewhat as a rectification column in that it provides for a partial separation of light from heavy oils. It will be understood that the scrubber may be operated in a great many different ways, when a scrubbing oil is used, depending upon the type of oil employed for scrubbing, the temperature of the oil, the temperature of the gas at the inlet, the temperature drop thru the scrubber, the quantity of scrubbing oil utilized, etc. In some cases the ratio of the sensible heat of the fixed gases to the latent heat of the oils to be condensed will be so high that a large amount of light oil will be vaporized. In such a case the method may be modified by the removal of a part of the sensible heat of the gases as sensible heat in the oil feed by adding a relatively cold oil. In some cases it will be desirable even to add with the oil a regulated amount of water which upon vaporization will remove to the degree desired the excess of heat in the gases.

Tar or pitch at atmospheric temperature or preheated to a greater or less extent, may be used for scrubbing the hot gases leaving the collector main. The residue drawn off from the scrubber will usually be at a higher temperature than the scrubbing medium entering the scrubber. The scrubbing operation may be so controlled that, due to the removal of entrained pitchy material from the gases and/or distillation by the hot gases in the scrubber, this residue will be a pitch of relatively high melting point. Such a hot residue, before it has an opportunity to cool, may

advantageously be added to the tar or pitch used for flushing the collector main.

From the scrubber the gases carrying condensable vapors can be conducted thru suitable condensing apparatus including coolers, scrubbers, fractional condensers, fractionating columns, etc., designed to reduce the temperature of the gases and to cause the separation of the oils therefrom. One total oil fraction may be collected if the gases are cooled in one step to the lowest desired temperature. Several oil fractions can be recovered if the gases are cooled by stages in coolers designed for the separate collection of oils corresponding to the individual cooling steps.

The high temperature of the hot coal distillation gases coming from the ovens or retorts, where cooling is prevented before they reach the collector main, enables them to effect more or less distillation in the collector main and still reach and pass through the scrubber at a sufficiently high temperature, e. g., at a temperature of 150° C. or 250° C. or higher, so that on subsequent cooling the total oil fraction may be utilizable as a creosote oil, containing oils boiling up to and above 350° C.; or by fractional cooling a heavier creosote oil and a lighter tar acid or carbolic oil can be recovered at successively lower temperatures. Simultaneously, pitches of regulated melting points can be produced by the distillation of tar in the collector main, and by scrubbing of the still hot and pitch-containing gases in the scrubber. Pitches of commercial qualities can thus be produced, e. g., pitches of 105-110° F. melting point, or of 150-160° F. melting point, or of 212 or 250° F. melting point or higher can be produced by the distillation in the collector main and/or from the scrubber.

As examples of the operation of the process, the gases can be passed through the collector main at a temperature such that they leave the main at 300° C. or 350° C. or even 400° C. or higher, with surface contact of the gases with the river of hot pitch flowing through the main and distillation thereof, and the hot gases, still at a high temperature, are passed to the scrubber and are there scrubbed with hot tar or pitch and freed from suspended pitch particles at a sufficiently high temperature to leave a large proportion of oils in vapor form. The gases and oil vapors may, e. g., leave the scrubber at a temperature around 150-160° C. or around 200° C. or even around 250° C. or higher. Pitch will be recovered from the scrubber, and clean oils on cooling of the hot cleaned and enriched gases.

The present invention is of more or less general application to the distillation of tar and oils and the recovery of clean oils therefrom and to the recovery of pitches and oils

directly from coke oven and other coal distillation gases, and it will be further illustrated by the following more detailed description taken with the accompanying drawings which show apparatus embodying the invention and adapted for the practice thereof. It is intended and will be understood that the invention is not limited to the specific details of the apparatus as illustrated in the drawings, in which

Fig. 1 is a plan view of a portion of a coke oven plant illustrating the application of the invention thereto; and

Fig. 2 is an enlarged sectional view illustrating the collector main and the scrubber connected therewith.

Referring to the drawings, 5 indicates a battery of coke ovens in which the individual ovens are connected by uptake pipes and 20 goose-necks 6 to a collector main 7 having a centre box 8. Tar or pitch to be distilled is supplied from a storage tank 9 by means of a pump 10 and a pipe or pipes 11 which may deliver the tar or pitch to the opposite 25 ends of the collector main, for example, in sufficient volume to maintain a large supply of hot thinly fluid tar or pitch in the collector main during the operation thereof. The tar or pitch flows through the collector 30 main to the centre box 8 and may be withdrawn therefrom through a pipe 12 and delivered to the tank 9' from which it may be recirculated for further distillation. A portion 35 of the tar or pitch may be withdrawn from the tank 9' through a pipe 13'. Additional quantities of tar for distillation can be introduced to the tank 9 through a pipe 14.

The hot gases flowing through the collector main after contact with the tar or pitch 40 therein, and after enrichment as the result of distillation with oil constituents, are withdrawn from the centre box 8 while still at a high temperature, e. g., around 300 to 400° C., and are delivered through a pipe 15 to 45 the scrubber which may be of any suitable form or construction. Preferably it consists of a shell 16 which may be filled with broken up tile or other suitable material adapted to bring the gases and liquid into intimate contact with each other. The gas is introduced 50 through an inlet 17 at the bottom of the scrubber and withdrawn through an outlet 18 at the top thereof. Tar, pitch or oil may be introduced at the top of the scrubber through 55 a pipe 19 from a source of supply thereof such as a tank 20, a pump 21 being provided to permit circulation. A heat exchanger 22 may be provided to permit regulation of the 60 temperature of the circulating pitch, tar or oil by the introduction of a heating or cooling medium to the exchanger.

After flowing downwardly over the baffles in the scrubber the unvaporized pitch, tar or oil can be withdrawn through an outlet 23. It may be delivered directly to

the tank 20 or, if water is present or condensed from the gasses, to a decanter 24 in which water or ammonia liquor is separated, the tar being then returned to the tank. Only in case water is present in the scrubbing medium, or the gases are cooled sufficiently to condense water from the gases, will water be present with the tar or oil. In most cases, a higher temperature of scrubbing will be used to maintain a large proportion of oils as vapors, and no water will be present or condensed. The scrubbing medium may be added continuously through pump 21 and withdrawn continuously through outlet 23' or the material may be led to tank 20 and recirculated. An additional scrubber or scrubbers (not shown) may be provided if desired, for fractional condensation or multi-stage scrubbing at progressively lower temperatures.

The gases escaping from the scrubber or scrubbers and being substantially free from "tar fog" and solid particles, and in most cases still at a high temperature, e. g., 150° or 200° C. or higher, may be delivered through a pipe 24' to a condenser 25. This condenser may be of any suitable form. The condenser shown is of the ordinary "wet" type which is employed frequently in by-product recovery systems. The gases and vapors are cooled therein by contact with grid surfaces wet by sprays of ammonia liquor, for example, and the resulting condensate is withdrawn through pipes 26 to a decanter 27 wherein the oil is separated from the ammonia liquor. The gases leave the condenser through a pipe 28 and are delivered to an exhauster 29 which maintains the pressure balance in the system. The gases may be conducted thence through the usual equipment (not shown) for the recovery of ammonia, light oils, etc.

The apparatus as described permits the distillation of tar and the production of pitch therefrom, and the utilization for this purpose of a portion of the heat in the coke-oven gases, and in particular it permits the operation of the collector main in a satisfactory manner, avoiding accumulation of hard pitch therein. The condensable oils, in accordance with the present invention, are largely retained in the gases as vapors and are increased by vapors from the distillation of tar or pitch in the collector main. The gases, while still hot, are cleaned by a scrubbing treatment and pitch or tarry oil separated therefrom, leaving clean or relatively clean gases and oil vapors. On cooling, clean or relatively clean oil condensates are obtained. Thus, the invention permits the recovery of clean oils and of pitches having the desired characteristics directly from the coke oven or other coal distillation gases, as well as the distillation of tar to produce pitch and oils, with resulting saving in the

cost of handling and of redistilling the ordinary products of a by-product recovery system.

From one standpoint, the invention includes improvements in the operation of the collector or hydraulic mains, of coke oven or gas retort systems, in which a river of hot tar or pitch is circulated through the main to keep it free from objectionable pitch accumulations, and to effect distillation of the circulating tar and pitch to a greater or less extent, combined with the scrubbing of the still hot and "tar fog"-containing enriched gases to remove the suspended pitch or heavy tar particles therefrom, while leaving oils largely in vapor form, and the subsequent condensation of clean or relatively clean oils therefrom. Separate pitch products can thus be produced by the distillation in the collector main, and from the gases in the scrubber, while a high yield of clean oils, suitable for creosoting or other purposes, can be condensed as a total oil fraction, or fractionally to give a series of oil products.

It will be understood that the foregoing description is illustrative of the invention and that various changes may be made in the form and arrangement of the apparatus and in the operation thereof without departing from the invention.

I claim:—

1. The method of producing pitch and oils at coal distillation plants, which comprises collecting gases from a plurality of the ovens or retorts and passing them through a common collecting main at a high temperature sufficiently high to bring about effective distillation of tar thereby, circulating through the collector main in direct contact with such gases a stream of hot thinly fluid tar and pitch, adding tar to the stream and effecting distillation of oils therefrom by direct contact with such gases, withdrawing the resulting stream of pitch from the main, withdrawing the gases from the main while still at a high temperature and scrubbing the gases while still at a high temperature with a hot scrubbing medium to separate suspended pitch particles therefrom and leave a large part of the oils in the form of vapors, and subsequently cooling the scrubbed gases and vapors to condense oils therefrom.

2. The method of producing pitch and oils at coal distillation plants, which comprises collecting gases from a plurality of the ovens or retorts and passing them through a common collecting main at a high temperature sufficiently high to bring about effective distillation of tar thereby, circulating through the collector main in direct contact with such gases a stream of hot thinly fluid tar and pitch, adding tar to the stream and effecting distillation of oils therefrom by direct contact with such gases, withdrawing the resulting stream of pitch from the main, withdrawing the gases

from the main while still at a high temperature, and scrubbing such gases with a liquid coal-tar-oil containing hydrocarbonaceous medium and simultaneously distilling oils from said medium by bringing the medium and gases into intimate contact with each other at a sufficiently high temperature to separate suspended pitch particles from the gases and leave a large part of the oils in vapor form, and subsequently cooling the scrubbed gases to separate oils therefrom.

3. The method of producing simultaneously different pitch products and also oils at coal distillation plants which comprises collecting gases from a plurality of the ovens or retorts and passing them through a common collecting main while still at a high temperature sufficient to effect distillation of oils, circulating through the collector main in direct contact with such hot gases a stream of hot thinly fluid coal-tar-oil containing hydrocarbonaceous material and effecting distillation of oils therefrom by direct contact with such gases, withdrawing the resulting stream of pitch from the collector main, withdrawing the resulting gases while still at a high temperature from the collector main and scrubbing them with a hot pitch scrubbing medium to separate suspended pitch particles from the gases and leave a large part of the oils in vapor form, withdrawing the resulting pitch product from the scrubbing operation, and subsequently cooling the scrubbed and enriched gases to condense oils therefrom.

4. The method of producing pitch and oils at coal distillation plants which comprises collecting gases from a plurality of the ovens or retorts and passing them through a common collecting main at a high temperature, circulating through the collector main in direct contact with such hot gases a stream of hot thinly fluid tar and pitch and effecting distillation of oils therefrom by direct contact with such hot gases, withdrawing the stream of pitch and recirculating part of it, together with additional tar through the collector main to effect further distillation, withdrawing the resulting gases enriched in oil vapors from the distillation from the collector main while still at a high temperature, scrubbing the gases to remove suspended pitch particles therefrom while still at a high temperature, and subsequently cooling the scrubbed gases to condense oils therefrom.

5. The method of producing pitch and oils at coal distillation plants which comprises collecting gases from the ovens or retorts and passing them through a common collecting main at a high temperature, sufficiently high to distill tar, circulating through the collector main in contact with such gases a stream of hot thinly fluid tar and pitch, adding tar thereto and effecting distillation of oils therefrom by direct contact with such gases, withdrawing the resulting stream of pitch from

- the collector main, withdrawing the gases from the collector main while still at a high temperature, and scrubbing such gases with the pitch drawn off from the collector main at a sufficiently high temperature to separate suspended pitch particles from the gases and leave a large part of the oils in vapor form, withdrawing the pitch resulting from the scrubbing treatment, and subsequently cooling the gases from the scrubbing operation for the condensation of oils therefrom.
6. The method of producing pitch and oils at coal distillation plants which comprises collecting the gases from the ovens or retorts and passing them through a common collector main at a high temperature such that the gases escape from the collector main at a temperature not less than 300° C., circulating through the collector main a stream of hot thinly fluid coal-tar-oil containing hydrocarbonaceous material in direct contact with such hot gases to effect distillation of the oils therefrom, withdrawing the resulting stream of pitch from the collector main, withdrawing the gases from the collector main at such high temperature, and scrubbing the gases while still at a high temperature to remove suspended pitch particles therefrom and to leave a large part of the oils in vapor form, and subsequently cooling the scrubbed gases to condense oils therefrom.
7. The method of producing pitch and oils at coal distillation plants which comprises collecting the gases from the ovens or retorts and passing them through a common collector main at a high temperature sufficient to effect distillation of tar, circulating through the collector main in contact with such gases a stream of hot thinly fluid tar and pitch, adding tar to the stream, withdrawing the gases from the collector main while still at a high temperature and scrubbing them with oils to separate suspended pitch particles from the gases and to effect partial distillation of the oils, withdrawing the residue from the oils together with the separated pitch, and subsequently condensing the gases to separate oils therefrom.
8. The method of producing pitch and oils at coal distillation plants, which comprises collecting the gases from the ovens or retorts and passing them thru a common collector main at a high temperature such that the gases escape from the collector main at a temperature not less than around 300° C., circulating thru the collector main a stream of hot thinly fluid coal-tar-oil containing carbonaceous material in direct contact with such hot gases to effect distillation of oils therefrom, withdrawing the stream of pitch from the collector main, withdrawing the gases from the collector main at such high temperature, scrubbing the gases to remove suspended pitchy particles therefrom and to leave a part of the oils in vapor form, adding

the scrubbing medium to the collector main, after it has been used to scrub the gases, and cooling the scrubbed gases to condense oils therefrom.

9. The method of producing pitch and oils at coal distillation plants, which comprises collecting the gases from the ovens or retorts and passing them thru a common collector main at a temperature sufficiently high to effect distillation of tar, circulating thru the collector main in contact with such gases, a stream of hot thinly fluid tar and pitch, adding tar to the stream, withdrawing the gases from the collector main while still at a high temperature, scrubbing them with oils to separate suspended pitchy particles from the gases and to effect partial distillation of the oils, withdrawing the residue from the oils together with the separated pitch and supplying it to the collector main, and subsequently condensing the scrubbed gases to separate oils therefrom.

10. A coal distillation plant having a plurality of coal distillation ovens or retorts, a common collecting main for collecting the gases from the ovens or retorts, no means being provided for spraying the gases with a cooling medium as they pass thru the collector main, a scrubber arranged near the collector main to act on the gases as they leave the collector main, means for circulating a stream of hot thinly fluid tar or pitch through the collector main and means for scrubbing the gases in the scrubber with a hot scrubbing medium, a condenser and means for passing the gases from the collector main to the scrubber and from the scrubber to the condenser, whereby the gases are employed for the distillation of tar or pitch in the collector main and are freed from suspended pitch particles in the scrubber before entering the condenser.

In testimony whereof I affix my signature.
